[57] CLAIM

The ornamental design for a vehicle exterior rear view
mirror, as shown and described.

DESCRIPTION

FIG. 1 is a perspective view of the vehicle exterior rear view
mirror embodying the design of the present invention;

FIG. 2 is a side elevational view thereof, the side opposite
being substantially a mirror image of the side shown
in FIG. 2;

FIG. 3 is a front elevational view thereof;

FIG. 4 is a rear elevational view thereof;

FIG. 5 is a top plan view thereof; and,

FIG. 6 is a bottom view thereof.

FIG. 1

FIG. 2

FIG. 3
